RAIN SHIELD FOR AUTOMOBILES

Everett S. Ottman, Rochester, N.Y.

Application July 15, 1958, Serial No. 51,790

Term of patent 14 years

(Cl. D14—6)

The figure is a perspective view of a rain shield for automobiles, showing my new design, the automobile on which the rain shield is mounted being fragmentarily illustrated in broken lines for purposes of illustration.

I claim:

The ornamental design for a rain shield for automobiles, substantially as shown and described.
